CLAIM

The ornamental design for a portable traction device, as
shown and described.

DESCRIPTION

FIG. 1 illustrates a top, right perspective view of an exemplary use of a portable traction device incorporating a first embodiment of the new design;

FIG. 2 illustrates a top, right perspective view of the portable traction device incorporating the first embodiment of the new design, the portable traction device illustrated in a flat, supine configuration;

FIG. 3 illustrates a front plan view thereof;

FIG. 4 illustrates a rear plan view thereof;

FIG. 5 illustrates a top elevation view thereof;

FIG. 6 illustrates a bottom elevation view thereof;

FIG. 7 illustrates a left side elevation view thereof;

FIG. 8 illustrates a right side elevation view thereof;

FIG. 9 illustrates a top, right perspective view of a portable traction device incorporating an alternative embodiment of the new design, the portable traction device illustrated in a flat, supine configuration;

FIG. 10 illustrates a front plan view thereof;

FIG. 11 illustrates a rear plan view thereof;

FIG. 12 illustrates a top elevation view thereof;

FIG. 13 illustrates a bottom elevation view thereof;

FIG. 14 illustrates a left side elevation view thereof; and,

FIG. 15 illustrates a right side elevation view thereof.

The broken lines in FIG. 1 depicting a user are for the
purpose of illustrating environment and form no part of the
claim. All other broken lines depict stitching and portions of
the portable traction device and form no part of the claim.

1 Claim, 5 Drawing Sheets
